CLAIM

The ornamental design for a syringe, as shown and described.

DESCRIPTION

FIG. 1 is a front, right and top perspective view of a syringe in accordance with our new design;

FIG. 2 is a front, left and bottom perspective view thereof;

FIG. 3 is a rear, left and top perspective view thereof;

FIG. 4 is a rear, right and bottom perspective view thereof;

FIG. 5 is a front perspective view thereof; and,

FIG. 6 is a rear perspective view thereof.

The broken lines in the figures are for the purpose of showing environmental structure and form no part of the claimed design.
